(Model.)

J. DESMOND
INJECTOR.

No. 554,415.

Patented Feb. 11, 1896.

UNITED STATES PATENT OFFICE.

JOHN DESMOND, OF DETROIT, MICHIGAN, ASSIGNOR TO THE PENBERTHY
INJECTOR COMPANY, OF SAME PLACE.

INJECTOR.

SPECIFICATION forming part of Letters Patent No. 554,415, dated February 11, 1896.

Application filed November 11, 1893. Serial No. 490,694. (Model.)

To all whom it may concern:

Be it known that I, JOHN DESMOND, a citizen of the United States, residing at Detroit, in the county of Wayne and State of Michigan, have invented certain new and useful improvements in Injectors, of which the following is a specification, reference being had therein to the accompanying drawings.

The invention consists in the peculiar construction, arrangement and combination of the parts, and particularly in the arrangement of the nozzles or jets, and the overflow valves and chambers forming simple and efficient means for automatically restarting the injector and for maintaining the stream under extremes of temperature of the feed-water and pressure of steam, all as more fully hereinafter described.

In the drawings, Figure 1 is a vertical central longitudinal section through an injector embodying my invention. Fig. 2 is a cross-section thereof on line *xx*.

A is the casing of the injector.

B is the steam-inlet branch, *C* the water-inlet branch, *D* the discharge or delivery branch, and *E* the overflow branch, to each of which suitable pipe connections may be made in the usual manner.

The body of the injector-casing is provided with a longitudinal passage containing the jets, and at each end this passage is capped by the caps or plugs *a* *b*, permitting access to the interior for the removal and insertion of the jets.

c is the steam-inlet tube or jet, *d* the suction-tube, *e* the combining-tube and *f* the delivery-tube, all in suitable relation to each other and secured in partitions in the casing to divide it into the steam-chamber *F*, the water-chamber *G*, the overflow-chamber *H* and overflow exhaust chamber *I*, and the delivery-chamber *J*.

From the delivery-chamber is a passage *K* connecting that chamber with the delivery branch *D* of the casing. From the overflow-chamber *H* is the overflow-discharge passage *g*, which is controlled by the valve *h*, preferably a gravity check-valve having a suitable stem engaging in a guideway *i* in the plug *k* secured in an aperture in the casing above

the check-valve, as plainly shown in the drawings.

From the chamber *I* is a discharge-port *m*, which port *m* communicates with the annular passage *n* around the main casing of the injector connected with the overflow branch *E*, as plainly shown in Fig. 2.

A valve *o* controls the port *m* from the chamber *I*, and this is provided with a winged stem *p* working in a guideway in the casing. Above the valve *o* is an apertured plug *q* having a valve-seat at its upper end upon which is seated the valve *r*. The plug *q* is held in position by means of the hollow screw-cap *s*, in which is the pressure-chamber *t* communicating with the delivery-chamber of the injector through the port or passage *u*. The valve *r* is provided on its under side with a winged stem *v* extending through the guideway in the plug *q* to the top of the winged stem *p* of the valve *o*.

The parts being thus constructed, their operation is as follows: Steam being admitted into the steam-inlet branch and water being supplied through the water-supply branch of the injector in the usual manner, the steam passing through the jets *c* *d* will open the valves into the overflow branch and create a partial vacuum in the chamber *g*, lift the water into and deliver it through the suction-tube into the chamber *H*, from which it will overflow into the chamber *I* and thence through the port *m* into the overflow-passage *n* and out through the overflow branch *E* of the injector. Such of the water as does not enter the delivery-tube will take the same course, and this will continue until the jet is formed through the combining and delivery tubes *e* *f*. As soon as the pressure becomes reduced in the chamber *H* the valve *h* will seat automatically and the water from the chamber *H* will be drawn into the combining-tube. The lifting of the valve *o* correspondingly lifts the valve *r* and opens the pressure-chamber to the overflow branch. As soon as the jet is established through the tubes the pressure increases in the delivery-chamber, and being communicated to the pressure-chamber *t* above the valve *r* forces the valve *r* to its seat, and this movement will also close *100*

the valve *o*. The chamber I being now closed such water as may be therein will be drawn out by the jet action and be discharged through the delivery-tube *f*.

5 In practice it has been found very difficult to make a valve such as *r* perfectly tight, and in case that valve leaks there is usually a continued drip at the overflow. Now I construct the valve *o* preferably so that it has a loose fit on its seat, or I may drill a small hole through that valve so that any leak past the valve *r* will fall upon the valve *o* and in flowing over the edge of said valve be drawn by the suction into the chamber I and be delivered through the delivery-tube to the boiler. In this way all leakage from the valve *r* is taken up without in any way affecting the operation of the machine.

What I claim as my invention is—

20 1. In an injector, the combination of the casing, partitions therein to form the communicating chambers *H I*, having an overflow common to both, the combining and delivery tubes having a spill-opening into the

chamber I, the valve *h* in the passage between the chambers and the valve *o* for the overflow located between the chamber I and overflow-passage, substantially as described.

2. In an injector, the combination of the casing, partitions therein to form the chambers *H I*, the overflow-passage *n*, discharge *D*, of the valves *h o* and *r*, substantially as described.

3. The combination of the combining and delivery chambers having a spill-passage therefrom, communicating with the chamber I, the valve *o* being constructed to permit fluid above the same to enter the chamber I and the valve *r* subject to pressure from the delivery and adapted to close the valve *o*, substantially as described.

In testimony whereof I affix my signature in presence of two witnesses.

JOHN DESMOND.
